CLAIM

The ornamental design for a grill brush, as shown and described.

DESCRIPTION

FIG. 1 is a side view of the disclosed grill brush;

FIG. 2 is a perspective view of the front of the grill brush; and,

FIG. 3 is a perspective view of the rear of the disclosed grill brush.

The broken lines shown in FIGS. 1–3 are included for the purposes of illustrating environmental elements only and form no part of the claimed design.

The grill brush is characterized by the shape of the grill brush.
